UNITED STATES PATENT OFFICE.

LOUIS MAURICE BARMAN, OF LONDON, ENGLAND, ASSIGNOR TO RONEO LIMITED, OF LONDON, ENGLAND, A BRITISH COMPANY.

ADDRESSING MACHINE OR LIKE PRINTING MACHINE.

Application filed August 21, 1922. Serial No. 583,423.

To all whom it may concern:

Be it known that I, LOUIS MAURICE BARMAN, a citizen of the United States of America, residing at Roneo Building, 5, Holborn, London, E. C. 1, England, Great Britain, have invented new and useful Improvements in Addressing Machines or Like Printing Machines, of which the following is a specification.

10 The present invention relates to improvements in addressing or like printing machines of the type wherein stencil cards are employed for printing names and addresses upon envelopes, wrappers, labels or 15 the like.

In addressing machines of this class a stencil card is removed from the hopper through the action of a reciprocating pusher member working in a slideway or track 20 which pushes the card along the slideway to a position between a segmented inking roller and a segmented presser roller where an envelope, wrapper or label is pushed under the card by hand, so that when the inking roller and the pressure roller meet they 25 press the envelope and stencil between them and print on the envelope from the stencil.

With such machines, when more than one impression is required from a stencil card 30 it is necessary to return the card, by hand, to its initial position for action by the pusher member.

Now, the present invention comprises an attachment for use with machines of this 35 class whereby a stencil card is automatically returned to its initial position for re-use.

The attachment comprises a device in the 40 nature of a hook, finger, or the like adapted to be moved into engagement with the front edge of the stencil card to return the stencil to its normal position after it has been used, for re-use.

The repeating device is capable of attachment to any stationary part of the machine provided the hook or finger can be brought into action upon the front edge of a stencil card, and the device will now be described with reference to the accompanying drawings whereon.

Fig. 1 illustrates an addressing machine to which the repeater device is attached.

Fig. 2 shows an elevational view of the repeater device.

55

Fig. 3 is a front view of the device.

Fig. 4 shows a front view of a modified manner of attaching the device to stationary part of the machine.

Fig. 5 is an elevational view of Fig. 4. 60

Figs. 6 to 9 show a further modification.

On the machine shown in Fig. 1, which illustrates one form of addressing machine, the hopper or magazine A containing the stack of stencils B is secured to a slideway or track C supported in brackets D from the main casting E. From one of the side frames of the hopper A are pivoted a pair of brackets or arms F which support a set of rollers G, one of which contacts at will, with an ink roller mounted in an ink container H, while the foremost roller imparts the ink collected thereover to a mutilated or segmented inking roller J carried on a shaft K the said roller being rotated by the handle or lever M. A pinion L (shown in dotted lines) is mounted on shaft K and drives a second pinion N, to the shaft O of which is secured a mutilated or segmented presser roller P (see Fig. 2). The pinion N drives a third pinion Q the crankshaft R of which operates through a connecting rod the reciprocating pusher member S which works in the slideway or track C to withdraw the lowermost stencil from the pile and position it between the rollers J. and P. for printing. The stencil card after use falls into the container T.

In the machine under consideration the 90 spindle K which carries the roller J. works within a stationary sleeve U and from the view shown in Fig. 2 and in a less clear manner in Fig. 1 it will be seen that the repeating device is used in conjunction with 95 the said sleeve U.

The re-positioning device, or repeating device for the stencil card comprises, a clip 1 for attachment to any convenient stationary part of the machine, such as the sleeve 100 U, the said clip being secured by means of a right angle plate 2 to a casing 3 containing a coiled flat spring 4, the free end of which is fashioned into a hook or finger 5 for engaging the stencil card B in the 105 manner shown in Fig. 2. The plate 2 is

bored out for the reception of a knob or lever 6 for regulating the position of the clip 1 and hook or finger 5 on the sleeve U, or other stationary part of the machine.

5 In operation the clip 1 is passed over the sleeve U in the manner shown in Fig. 2 and in the normal or inoperative position the flat spring 4 with its hook 5 depends from the casing 3 above the path of the 10 stencil B so that the hook does not engage the forward edge thereof.

If the machine is worked with an empty hopper or magazine A and only one stencil in the slideway then the knob 6 is given 15 an upward pressure so that the spring 4 and hook 5 is brought into action against the forward edge of the stencil. On turning the handle M in a clockwise direction, the pusher member S acts on the rear edge 20 of the stencil B and pushes it along the slideway C until it is placed in the path of the mutilated inking roller J and the presser roller P. At this point an envelope, label, wrapper or the like is passed by hand 25 under the stencil. When the rollers J and P meet they grip the card B and envelope and carry them along the slideway C. At the same time the forward edge of the stencil card engages the hook 5 of the spring 4 30 and the movement of the card under the action of the rollers J and P causes the spring 4 to be withdrawn from the casing 3. The envelope is printed from the stencil card between the rollers J and P and when 35 the latter cease to grip the stencil card the said card is returned to its normal position in the slideway C, beneath the hopper A by the spring 4 which recedes into the casing 3. The next forward stroke of the pusher member S advances the stencil card for 40 further use, and the action is repeated until the hook 5 of spring 4 is raised by the knob 6 out of the path of the stencil card.

In cases where re-prints from a card are 45 required while a stack of stencils remain in the hopper or magazine A; when the pusher member S has withdrawn the stencil, the lever V is depressed in the direction of the arrow, and this depression causes a T- 50 shape piece W to rise and lift the stencil B clear of the pusher member as clearly shown in Fig. 1.

In Figs. 4 and 5 a modified method of 55 securing the repeating device to a stationary part of an addressing machine is shown. From these views the casing 3, spring 4 and hook or finger 5 are secured to the main casting E of the machine by right angle plate 2'.

The hook end of the spring 4 passes 60 through a slot 7 formed on a slide 8 adjustably secured to the main casting E by screws and washers 9 which pass through slots 10 in slide 8 the said slide being fitted with a knob 11.

65 As will be seen from Fig. 4, if a down-

ward movement is afforded to the slide 8 by the knob 11 the hook 5 of spring 4 will be brought below the level of the forward edge of the stencil card and thus put the repeating device out of action. 70

Referring now to the Figs. 6 to 9 of the drawings, Fig. 6 is a plan view of part of the slideway or track showing one side standard A.

Fig. 7 is a cross sectional view of one side 75 of the slideway or track to which is shown the device for acting upon the stencil card, in the inoperative position.

Fig. 8 is a similar view to Fig. 7, but depicting the device in its operative position. 80

Fig. 9 is a sectional view through the centre of the slideway looking towards the front or operative side of the machine.

On these views a tube 12 is fitted at one end over a lug formed on one side standard 85 A while the other end of the tube is supported on a lug carried by the cross piece X from which the container T is carried. The lug on the cross piece X is also provided with a fixed pin 13 which determines the 90 amount of movement to be given to the tube 12 by reason of the slot 14 fashioned at the end of the tube when the lever 15 secured to the tube is moved from the position shown in Fig. 7 to that illustrated in Fig. 95 8. The tube 12 is moreover fashioned with a central slot 16. See Fig. 9 in which works a finger 17 secured to a rod or tube 18 which is moved against the action of a spring 19 by the stencil card B when the tube occupies 100 the position shown in Fig. 8. When the finger 17 is in its lowered position (Fig. 8) the advance of a stencil card B by the rollers J and P causes the edge of the stencil to abut against the finger 17 and push it along 105 the slot 16 of tube 12 so that the spring 19 is compressed. When the rollers J and P release the card B the finger 17 under the action of the spring 19 returns the stencil card to its initial position for re-printing. 110

It will be understood that the invention is not limited to the exact methods shown and described for attaching the device to the machine, as these may require variation to suit existing types of addressing or like printing machines. 115

Having thus described my invention, what I desire to secure by Letters Patent of the United States is as follows:—

1. The combination with an addressing or like printing machine having means to print an impression from a stencil card or the like, of means to engage a stencil and return it for repeated printing operations, comprising a member projecting into the path of movement of said stencil and means connected with said member to cause said member and stencil to be returned to initial position. 120

2. The combination with an addressing 125

or like printing machine, having means to print an impression from a stencil card or the like, and means to feed said card from an initial position to and through said printing means, of an attachment adapted to be detachably secured to the machine, said attachment comprising a projection adapted to be moved into the path of the stencil as it passes through the machine and means connected with said projection to cause it to engage with said stencil and return the same to its initial position.

3. In addressing or like printing machines a device for re-positioning a stencil card comprising a spring, a hook or finger adapted to engage the edge of the stencil card, a casing for said spring and means for attaching said casing to a stationary part of the machine.

20 4. In addressing or like printing machines a device for returning a stencil card to its initial position for re-use comprising a spring, a hook or finger formed on said spring adapted to engage the edge of the stencil card during the printing from said card, a casing for said spring and a clip secured to said casing for attachment to a stationary part of the machine.

5. For addressing or like printing machines a device or attachment adapted to be moved into the path of a stencil card to

engage the forward edge of said card to return it after use to its initial position comprising a casing having means thereon for securing the same to the main casting, a 35 spring contained in said casing a hook or finger on said spring, and means for raising said hook and spring into the path of the stencil card.

6. A device for returning a stencil card to its initial position for re-use comprising a casing attached to a stationary part of the addressing machine, a spring carried by said casing, a slide adjustably secured to said machine having a slot for the reception 45 of the spring, a hook or finger at the end of the spring, and a knob on the slide for bringing the hook of the spring into or out of engagement with the forward edge of the stencil card. 50

7. A device for returning a stencil card to its initial position for reprinting therefrom comprising a tube supported in proximity to the plane of the slideway or track a lever for turning said tube, a pin limiting the 55 turning movement, a spring contained in said tube and a finger operating in a slot in said tube when acted upon by the edge of a stencil card.

In testimony whereof I have signed my 60 name to this specification.

LOUIS MAURICE BARMAN.
